US00D998049S

(12) **United States Design Patent** (10) **Patent No.:** **US D998,049 S**
(45) **Date of Patent:** **** Sep. 5, 2023**

(54) **GAMING MACHINE HAVING A CURVED DISPLAY**

(71) Applicant: **Video Gaming Technologies, Inc.**, Franklin, TN (US)

(72) Inventors: **Ryan Cuddy**, Reno, NV (US); **Paul Mellender**, Waltham, MA (US)

(73) Assignee: **Video Gaming Technologies, Inc.**, Franklin, TN (US)

(**) Term: **15 Years**

(21) Appl. No.: **29/696,820**

(22) Filed: **Jul. 1, 2019**

Related U.S. Application Data

(63) Continuation of application No. 15/333,614, filed on Oct. 25, 2016, now Pat. No. 10,363,480, which is a continuation-in-part of application No. 14/145,752, filed on Dec. 31, 2013, now Pat. No. 9,478,097.

(57) **CLAIM**

We claim the ornamental design for a gaming machine having a curved display, as shown and described.

DESCRIPTION

The FIGURE is a front perspective view of a gaming machine having a curved display showing our new design. The broken lines in the drawing illustrate unclaimed environmental features of the gaming machine and form no part of the claimed design.
